UNITED STATES PATENT OFFICE

CHARLES W. DAKE AND WILLIAM A. WULLE, OF CHICAGO, ILLINOIS, ASSIGNEES TO THE PYLE-NATIONAL COMPANY, OF CHICAGO, ILLINOIS, A CORPORATION OF NEW JERSEY

CAB SWITCH FOR LOCOMOTIVES AND THE LIKE

Application filed October 3, 1928. Serial No. 309,925.

Our invention relates to improvements in cab switches for locomotives and the like and has for one object to provide a new and improved form of switch structure and arrangement which lends itself to use with locomotive electrical equipment and which provides a special rigid, durable, dust, oil, steam and moisture-tight housing wherein the controlling members are easily accessible and where-
in the hand operated members are easily accessible and the electric controlling members are adequately protected.

The invention is illustrated more or less diagrammatically in the accompanying drawings wherein:

- 15 Figure 1 is a side elevation;
- Figure 2 is a front view;
- Figure 3 is a bottom plan view;
- Figure 4 is a view with the cover removed;
- 20 Figure 5 is a detail of the switch blades and conducting members up-side-down;
- Figure 6 is a section along the line 6—6 of Figure 2;

Figure 7 is a detail of the switch connec-
25 tions; and

Figure 8 is a detail of one of the hand control members.

Like parts are indicated by like characters throughout the specification and drawings.

20 A is a housing or box, closed at the bottom and provided with the flanges A¹ perforated at A² whereby the housing or box may be bolted or fastened in place. Associated with these flanges at their upper ends are sleeves A³ in which engage the conduits A⁴ through which the electric wires are brought to the interior of the housing.

A⁵ is a cover, grooved as indicated at A⁶, the groove containing a flexible packing gas-
25 ket A⁷ to engage the walls of the housing; the cover being held in place by the screws A⁸ to make an inclosed, dust and oil-tight box.

B is a quadrant on the outer face of the cover A⁵ having a plurality of latch aper-
30 tures B¹ and stop lugs B², one at each end of the quadrant. B³ is a switch handle mounted on the spindle B⁴, which spindle is rotatable in the hub B⁵ in the center of the cover. B⁶ is a spring-pressed latch upon
35 the quadrant B whereby the angular excur-

sion of the switch handle is limited by the stop blocks and may be locked in intermediate positions by engagement between the stop B⁶ and the ports in the quadrant. Ex-
tending downwardly from the lower end of the spindle B⁴ is a drive plate B⁷ from which project conical fingers B⁸, which fingers, when the handle B³ is rotated, operate the switch, as will hereinafter appear.

C is an insulating block. It is held in place in the housing by the three holding screws C¹. Arranged about the periphery of this insulating block C are a plurality of perforations C², each terminating in a pocket on the underside of the block C, which pockets are all closed by the single plate C⁴. Each of these perforations or pockets contains a binding post screw C³ projecting upwardly from the insulating block into the area of the housing. There are, as indicated in Figure 7, seven of them and each one is identical except that it makes an electrical connection for different purposes.

C⁵ is a hub recessed in the insulating block C and provided with two angularly spaced conductor arms C⁶, each one of them associated with one of the binding posts or screws C³. This hub carries a pivot pin C⁷ on which is rotatably mounted the two discs C⁸, having each a pair of diametrically opposed spring contact fingers C⁹. Supported on these plates C⁸ is an insulating drive disc C¹⁰, the disc and plates being connected by a pair of pins C¹¹. The drive disc C¹⁰ has two diametrically opposed apertures containing bearing sleeves C¹² adapted to engage the pins B⁶ whereby rotation of the handle B³ causes rotation of the spring clip switches C⁹.

It will be noted that a conductor D is in electric circuit with one of the fingers C⁹ to energize the contact fingers C⁹.

It will be noted that the three spaced contact fingers E, E¹, E² are each provided with binding posts to which a conductor leads so that rotation of the handle B³ closes the circuit through some one of the fingers E, E¹, E², but it will be noticed also that the angular arrangement of these fingers is such that the spring fingers C⁹ can never touch more than one of the contacts E, E¹, E² at a time.

On the periphery of the insulating block C but far enough out not to be interfered with by the spring contact members C⁹, are two upwardly extended contact springs F in opposition one to another, and each of them 5 is in circuit with a conductor as indicated. F¹ is a switch having two irregularly shaped insulating blocks F² and a single conductor block F³, the relation of the parts being such that when in one rotated position the insulating blocks spread the fingers F, F³ apart and when in another position the insulating blocks are out of register and the sleeve F³ 10 forms an electric circuit between them. It will be noted that the pin F⁴ is slideable in a boss F⁵ in the wall of the housing, a spring F⁶ being provided tending to hold the pin inwardly to cause interlocking between the notch F⁷ upon the boss F⁵ and a lock F⁸ on the handle F⁹. The handle may be pulled 15 back, compressing the spring to permit rotation, thereby providing a positive engagement and disengagement of the switch.

If it is desired to make electric contacts 20 with the interior of the housing and with the switches therein other than through the conduits A⁴, binding posts G, G¹ are provided, set into the wall of the housing so that if wires are brought to these binding posts and 25 as wires are taken from them to a more suitable part of the switch interior, circuits may be closed, just as through the conduits themselves.

We claim:

- 35 1. In combination a switch housing and cover, a control handle on the outside of the cover, a fork on the inside adapted to rotate with the control handle, a switch member, an insulated actuating plate having perforations adapted to be engaged by the fork whereby 40 rotation of the fork causes rotation of the switch and whereby removal of the cover automatically disengages the fork and the plate.
- 45 2. In an electric switch, a recessed insulated base, a supporting hub in said recess, a plurality of inclined radial arms extending outwardly from the hub to the periphery of the plate, a pivot pin carried by the hub and a 50 rotating switch member mounted on said pivot pin.
- 55 3. In an electric switch, a recessed insulated base, a supporting hub in said recess, a plurality of inclined radial arms extending outwardly from the hub to the periphery of the base, a pivot pin carried by the hub and a 55 rotating switch member mounted on said pivot pin, a rotating switch member comprising a pair of spaced parallel switch discs, 60 spring fingers projecting from the periphery of said discs in opposed pairs, an insulated actuating plate, a plurality of pins spacing the plate from the switch discs, the plate being perforate, an actuating fork having 65 fingers adapted to penetrate the perforations.

4. In combination, a switch housing and cover, a control handle on the outside of the cover, a fork on the inside adapted to rotate with the control handle, a switch member, an insulated actuating plate located in a plane 70 perpendicular to the axis of rotation of the switch member overlying the switch member, projecting beyond it and shielding it from the cover, the plate being perforated, the perforations being adapted to be engaged by the fork in the handle whereby movement of the handle causing rotation of the fork rotates the switch.

Signed at Chicago, county of Cook and State of Illinois, this 15th day of September, 1928.

CHARLES W. DAKE.
WILLIAM A. WULLE.
